UNITED STATES PATENT OFFICE.

JOSEPH A. COSTELLO, OF CLEVELAND, OHIO, ASSIGNOR TO THE CLEVELAND BRASS MANUFACTURING COMPANY, OF CLEVELAND, OHIO, A CORPORATION OF OHIO.

FAUCET.

Application filed April 10, 1922. Serial No. 551,117.

To all whom it may concern:

Be it known that I, JOSEPH A. COSTELLO, a citizen of the United States, residing at Cleveland, in the county of Cuyahoga and 5 State of Ohio, have invented a new and useful Faucet, of which the following is a specification.

This invention relates to improvements in faucets more especially adapted for use in 10 connection with oil-tank wagons and comprising a casing having an interior chamber which has an inlet for receiving oil or liquid from a tank or reservoir and also having a spout extending downwardly from 15 and arranged to communicate with said chamber, a valve controlling communication between said chamber and the spout and arranged to move in said chamber in opening, means acting to retain the valve in its 20 closed position, a shaft arranged below the valve and extending from the exterior of the spout at one side of the spout into and transversely of and supported from the spout, and a cam operatively mounted on 25 the shaft internally of the spout and having the dimensions, contour and arrangement required to actuate the valve from its closed position into its open position during the rotation of the shaft in the required direction.

One object of this invention is to render the valve-operating means comprising said shaft simple and durable in construction and highly practical.

Another object is not only to have a terminal portion of the said shaft arranged at the exterior of the spout and there to be operatively engaged by a key, wrench or device for rotating the shaft, and to provide the spout with a stuffing-box around the shaft between said portion of the shaft and the interior of the spout, but to have a chamber formed, next and around said portion of the shaft, interiorly of the outer end 45 portion of the gland of said stuffing-box and extending to the outer extremity of said gland, and to provide simple and improved means for preventing the application of a key, wrench or shaft-rotating device, when desired, into operative engagement with said portion of said shaft.

Another object is to facilitate the manufacture and assemblage of the component parts of my improved faucet.

With these objects in view, and to attain

any other object hereinafter appearing, this invention consists in certain features of construction, and combinations and relative arrangements of parts, hereinafter described in this specification, pointed out in 60 the claims, and illustrated in the accompanying drawings.

In said drawings, Figures 1 and 2 are central vertical sections of a faucet embodying my invention and show the valve of the 65 faucet closed and open respectively. Fig. 3 is a vertical section taken along the line 3—3 in Fig. 1, looking inwardly. Fig. 4 is a right-hand side view in relation to Fig. 3. Figs. 5 and 6 are horizontal sections taken 70 along the line 5—5 and line 6—6 respectively in Fig. 1, looking downwardly. Fig. 7 is a side elevation corresponding with Fig. 4, except that in Fig. 4 a movable guard-arm is locked in a position in which said 75 arm prevents the required access to the shaft for rotating the shaft, whereas in Fig. 7 said arm is shown swung out of the way of said shaft. Fig. 8 is a side view of said shaft detached. Fig. 9 is a transverse section taken along the line 9—9 in Fig. 8, looking inwardly. Fig. 10 is a cross-section at line 10—10 in Fig. 8. Fig. 11 is a transverse section taken along the line 11—11 in Fig. 8, looking inwardly.

Referring to said drawings, 15 (see Figs. 1, 2 and 5) indicates a metal casing having an interior chamber 16 and also having a preferably integral spout 17 which extends downwardly from and is arranged to communicate with said chamber. At one side of the chamber 16 the casing 15 has a laterally and outwardly projecting and internally screw-threaded tubular member 18 which forms the inlet of said chamber and 90 is adapted to be threaded onto a tank-wagon pipe or other liquid-supplying pipe or tubular member not shown.

The casing 15 (see Figs. 1, 2 and 5) is provided internally, at the upper end of the 100 spout 17, with an upwardly facing annular valve-seat 20 extending around the upper end of the passage formed by and interiorly of the spout, and a valve 21, which controls communication between said spout and the 105 chamber 16, engages said seat in the closed position of the valve, as shown in Fig. 1, and is movable upwardly in said chamber in opening. Said valve is provided centrally with an upwardly projecting stem 22 110

which extends into a chamber 23 extending upwardly from the lower end and formed interiorly of a metal head 25 which is threaded at its lower end portion into the upper portion of and therefore removable from the casing 15. A coiled spring 26 is coiled around the stem 22 and confined between the valve 21 and the upper end wall of the chamber 23 and acts to retain the valve in its closed position.

Improved means for actuating the valve 21 from its closed position shown in Fig. 1 into its open position shown in Fig. 2 are provided and comprise a substantially horizontal shaft 27 which is arranged in and transversely of the spout 17 and below the downwardly projecting portion 28 of the central part of the valve 21, and preferably said shaft (see Fig. 6) has bearing in diametrically opposite portions of and is therefore supported from the spout. Preferably the shaft 27 (see Fig. 1) is spaced somewhat laterally of a point vertically below the center of the valve 21 and extends (see Fig. 6) from the exterior of the spout at one side of the spout into the spout and has an externally circular diametrical enlargement 29 at said side of the spout and a terminal portion 30 which is square or angular in cross-section, as shown in Fig. 11, and spaced outwardly from said enlargement to permit the application, to said terminal portion of the shaft, of a key, wrench or other device (not shown) for rotating the shaft. The spout 17 (see Fig. 6) has a portion 31 thereof overlapping the inner end face of and serving as an abutment for the enlargement 29 of the shaft. The shaft 27 (see Fig. 6) is provided internally of the spout 17, with an external annular shoulder 32 facing in the direction in which said end face of said enlargement 29 of the shaft faces, and a nut 33 is threaded onto the shaft and arranged opposite and spaced from said shoulder. The shaft 27 is shown detached in Figs. 8, 9, 10 and 11.

A cam 35 (see Figs. 1, 2 and 6) is operatively mounted on the shaft 27 between the shoulder 32 and the nut 33. Preferably the shaft 27 has its portion which extends from said shoulder toward said nut square or angular in cross-section, as shown in Figs. 1 and 2, and the cam 35 surrounds and conforms to said portion of the shaft and is preferably clamped by and between said nut and said shoulder. The cam 35 is therefore rotatable with the shaft. The cam 35 has such dimensions, contour and arrangement that the cam, in the closed position of the valve, is arranged to engage the lower end face of the downwardly projecting portion 28 of the valve and actuate the valve from its closed position shown in Fig. 1 into its open position shown in Fig. 2 during the rotation of the shaft in the direction and to

the extent required, and I would here remark that preferably the casing 15 and the cam 35 have portions thereof relatively arranged as required, as shown at 36 in Fig. 2, to cooperate in forming a stop for arresting rotation of the cam in said direction. Preferably the cam 35 (see Figs. 1 and 2) has an arm 37 arranged to cooperate with an internal surface 38 of the spout 17 in forming a stop for arresting rotation of the cam upon the rotation of the shaft in the direction and to the extent required to permit movement of the valve from its open position shown in Fig. 2 into its closed position shown in Fig. 1.

The spout 17 (see Figs. 3, 4 and 6) is provided, adjacent the diametrical enlargement 29 of the shaft 27 with a laterally and outwardly projecting tubular member 40 which (see Fig. 6) surrounds and affords bearing to said enlargement and also surrounds the shaft and forms the casing of a stuffing-box and measures more in internal diameter between its outer extremity and said enlargement of the shaft than at said enlargement so as to effect the formation, internally of said tubular member, of an annular shoulder 41 which is substantially flush with the outer end face of said enlargement of the shaft and faces in the direction of the outer end of said tubular member. The gland 42 of the hereinbefore mentioned stuffing-box (see Fig. 6) is threaded into and therefore removable from the tubular member 41 and surrounds the shaft 27 between the terminal portion 30 of the shaft and the packing 43 which is interposed between the inner end face of said gland and the shoulder 41 and between said face and the outer end face of the enlargement 29 of the shaft. The outer end portion of the gland 42 has an interior chamber 45 formed next and around the terminal portion 30 of the shaft 27 and extending to the outer extremity of said gland.

The casing 15 (see Figs. 3, 4, 5 and 7) is provided, adjacent the inner end of the inlet-forming tubular member 18, with a guard-arm 46 arranged externally of the casing and pivoted substantially horizontally, as at 47, to the casing at and depending from a point spaced upwardly from the shaft 27 and laterally of the shaft in the direction of said inlet-forming member 18. Said arm 46 has its axis substantially parallel with the shaft 27, and said arm is inoperative or operative according as it is in the position shown in Fig. 7 or in the position shown in Figs. 3, 4, 5 and 6. Said arm 46 has the arrangement and dimensions required to extend, in the operative position of the arm, as shown more clearly in Figs. 4 and 6, opposite the outer end of the chamber 45 and opposite the outer end face of the terminal portion 30 of the shaft 27, and the outer or free end portion of said arm has

such arrangement and dimensions that said portion of said arm, in said position of the arm, constitutes a shield covering said face of said portion of the shaft and arranged to prevent the insertion, into said chamber 45, of a key, wrench or device for rotating the shaft. Said arm 46 is retained and locked in its operative position as will hereinafter appear and adapted, when unlocked and released, to swing by gravity from its operative position shown in Figs. 3, 4, 5 and 6 into its inoperative position shown in Fig. 7.

15 The guard-arm 46 is provided, at its side which faces in the direction in which said arm swings during the actuation of the arm from its inoperative position shown in Fig. 7 into its operative position shown in Figs. 3, 4, 5 and 6, with an outwardly projecting ear 48 20 preferably arranged centrally between the ends of the arm, and the casing 15 is externally provided with an outwardly projecting ear 49 arranged to cooperate with the ear 48 of said arm for limiting movement of 25 said arm in said direction and furthermore arranged to register with the ear 48 of said arm in the operative position of the arm so as to permit the application of the bow 51 of a pad-lock 50 to said arm for holding and 30 locking said arm in its operative position when the arm is to be locked in its operative position in the closed position of the valve. Obviously removal of the lock 50, when the guard-arm 46 is held in its operative position 35 by said lock, is required to render said arm free to move into its inoperative position shown in Fig. 7, and therefore from opposite the outer end of the chamber 45, as required to permit the application, to the terminal 40 portion 30 of the shaft 27, of a key, wrench or device for rotating the shaft.

The casing 15 is also provided externally with a hook 52 from which may be suspended a receptacle which is to receive oil or liquid discharged from the spout 17, and it will be observed that said hook and the inlet-forming member 18 of the casing are arranged at opposite sides respectively of the casing and that the guard-arm 46, being supported from the casing adjacent said member 18, is out of the way of said hook.

It will be observed (see Fig. 2) that not only has the casing a stop-forming portion, as at 36, arranged to limit the rotation of the cam 35 in actuating the valve into its open position, but that the portion 28 of the valve, in the fully open position of the valve, exerts pressure downwardly on the cam at a point substantially vertically above the axis of the shaft 27, or between said point and said portion of the casing, and that the cam, in said fully open position of the valve, as shown in Fig. 2, is arranged to be held in such position by the valve and pressed 65 against said portion of the casing so as to

insure the retention of the valve in said fully open position until after the cam, by the required operation of the shaft, has begun to be actuated in the direction required to permit lowering of the valve.

What I claim is—

1. A faucet comprising a casing having an interior chamber which has an inlet and also having a spout arranged to communicate with said chamber, a valve controlling communication between said chamber and the spout, means for actuating the valve from its closed into its open position and comprising a shaft which extends from the exterior of the spout at one side of the spout into and is supported from the spout and at said side of the spout has a terminal portion to be operatively engaged by a shaft-rotating device, a guard-arm arranged externally of the casing and pivoted to the casing at a point spaced from the shaft, the spout having a stuffing-box extending around the shaft between the aforesaid portion of the shaft and the interior of the spout and comprising a gland the outer end portion of which has an interior chamber formed next and around the shaft and extending to the outer extremity of the gland, the outer or free end portion of said arm having the arrangement and dimensions required to form a shield which, in one position of said arm, is arranged opposite the outer end of the last-mentioned chamber, and means for holding and locking said arm in said position. 75 80 85 90 95

2. A faucet comprising a casing having an interior chamber which has an inlet and also having a spout arranged to communicate with and extending downwardly from said chamber, a valve controlling communication between said chamber and the spout, means for actuating the valve from its closed into its open position and comprising a shaft extending from the exterior of the spout at one side of the spout into and supported from the spout and at said side of the spout having a terminal portion to be operatively engaged by a shaft-rotating device, a guard-arm arranged externally of the casing and pivoted to the casing at a point spaced upwardly from and laterally of the shaft and having its axis substantially parallel with the shaft, the spout having a stuffing-box which extends around the shaft between the aforesaid portion of the shaft and the interior of the spout and comprising a gland the outer end portion of which has an interior chamber formed next and around said portion of the shaft and extending to the outer extremity of said gland, and the lower portion of the aforesaid arm having the arrangement and dimensions required to extend, in one position of said arm, opposite the outer end of the last-mentioned chamber, and means for holding and locking said arm in said position.

3. A faucet comprising a casing having an interior chamber which has an inlet and also having a spout arranged to communicate with said chamber, a valve controlling communication between said chamber and the spout, means for actuating the valve from its closed into its open position and comprising a shaft which extends from the exterior of the spout at one side of the spout into and is supported from the spout and at said side of the spout has a terminal portion, a guard-arm arranged externally of the casing and pivoted, adjacent the aforesaid inlet, to the casing, the spout having a stuffing-box which extends around the shaft between the aforesaid portion of the shaft and the interior of the spout and comprises a gland the outer end portion of which has an interior chamber formed next and around said portion of the shaft and extending to the outer extremity of the gland, and the free end portion of said arm having the arrangement and dimensions required to form a shield which, in one position of said arm, extends opposite the outer end of the last-mentioned chamber and covers the end face of said portion of the shaft, and means for holding and locking said arm in said position.
4. A faucet comprising a casing having an interior chamber which has an inlet and also having a spout arranged to communicate with said chamber, a valve controlling communication between said chamber and the spout, means for actuating the valve from its closed into its open position and comprising a shaft extending from the exterior of the spout at one side of the spout into and supported from the spout and at said side of the spout having a terminal portion, and a guard-arm arranged externally of and pivoted to the casing, the spout having a stuffing-box which extends around the shaft between the aforesaid portion of the shaft and the interior of the spout and comprises a gland surrounding said portion of the shaft and having in its outer end portion an interior chamber which is formed next and around said portion of the shaft and extends to the outer extremity of the gland, the aforesaid arm having the arrangement and dimensions required to extend, in one position of the arm, opposite the outer end of the last-mentioned chamber and having an ear, and the casing being provided externally with an ear which, in said position of said arm, registers with the ear of said arm.
5. A faucet comprising a casing having
- an interior chamber which has an inlet and also having a spout arranged to communicate with said chamber, a valve controlling communication between said chamber and the spout, valve-actuating means comprising a shaft extending from the exterior of the spout at one side of the spout into and supported from the spout and at said side of the spout having a terminal portion, a guard-arm arranged externally of and pivoted to the casing at a point adjacent the inner end of the aforesaid inlet, the spout having a stuffing-box extending around the shaft between the aforesaid portion of the shaft and the interior of the spout, said stuffing-box comprising a gland which surrounds said portion of the shaft and has an interior chamber formed next and around said portion of the shaft and extending to the outer extremity of the gland, the aforesaid arm having the arrangement and dimensions required to extend, in one position of the arm, opposite the outer end of the last-mentioned chamber and having a projecting member, and the casing having a projecting member arranged to limit movement of said arm in one direction, and means for attaching and locking said projecting member of said arm, in said position of the arm, to said projecting member of the casing.
6. A faucet comprising a casing which has an interior chamber having an inlet and comprises a spout extending downwardly from and adapted to communicate with said chamber and is provided internally with an upwardly facing valve-seat extending around the upper end of the passage formed by and within the spout, a valve arranged to engage said seat in its closed position, means acting to retain the valve in its closed position, a shaft arranged below the valve and transversely of the spout, and a cam mounted on and rotatable with the shaft and arranged to actuate the valve from its closed position into its open position during the rotation of the cam in the required direction, the casing having a stop-forming portion arranged to limit the rotation of the cam in actuating the valve from its closed position into its open position, and the cam being arranged, in the fully open position of the valve, to be held in such position by the valve and pressed against said portion of the casing.

In testimony whereof, I sign the foregoing specification, this 30th day of March, 1922.

JOSEPH A. COSTELLO.
